UNITED STATES PATENT OFFICE.

THOMAS JOSEPH EDWARD MOLDON, OF PETERBOROUGH, ONTARIO, CANADA.

EXPLOSION-ENGINE.

No. 895,099.

Specification of Letters Patent.

Patented Aug. 4, 1908.

Application filed August 3, 1905. Serial No. 272,474.

To all whom it may concern:

Be it known that I, THOMAS JOSEPH EDWARD MOLDON, a subject of the King of Great Britain, residing at Peterborough, county of Peterborough, in the Province of Ontario, Canada, have invented certain new and useful Improvements in Explosion-Engines; and I do hereby declare that the following is a full, clear, and exact description of the invention, such as will enable others skilled in the art to which it appertains to make and use the same.

My invention relates to improvements in explosion engines, and it consists in the constructions, combinations and arrangements herein described and claimed.

The object of my invention is to provide a compact form of explosion engine adapted to produce great power with a high degree of efficiency, and free from the defects incident to the employment of valves in such type of engines, such as chattering, distortion of the valve and its seat under large ranges of temperature, etc.

In the accompanying drawings, forming part of this application and in which similar reference symbols indicate corresponding parts in the several views—Figure 1 is a side elevation, illustrating one embodiment of my invention; Fig. 2 is a vertical, axial, sectional view of the construction shown in Fig. 1; Fig. 3 is a sectional view, on the line 3—3 of Fig. 2; Fig. 4 is a sectional view, on the line 4—4 of Fig. 2; Fig. 5 is a sectional view, on the line 5—5 of Fig. 2; Fig. 6 is a sectional view, on the line 6—6 of Fig. 4, with the pistons, engine shaft, and intermediate connections omitted for the sake of clearness; and Fig. 7 is a sectional view on the line 7—7 of Fig. 4, with the pistons, engine shaft, and intermediate connections omitted for the sake of clearness.

Referring to the drawings, 1 indicates two similar casings, each of which is provided with an explosive cylinder 2, pump cylinder 3, and a water jacket 15 for said cylinders; said casings being provided with flanges 33, for securing them together about an engine crank shaft 6^a and with pipes 16 for maintaining a circulation of water through the jackets 15.

Oppositely disposed differential pistons are connected by connecting rods 13 to a common crank 6 on said engine shaft 6^a; each of said differential pistons comprising an engine piston 7 and a pump piston 8, re-

ciprocatingly mounted in the corresponding engine cylinder and pump cylinder.

The connecting rods 13 are bifurcated at their crank ends; collars 14 being provided for maintaining said bifurcated ends in engagement with the crank 6.

The engine cylinders are provided with any usual form of sparking device 27, and with lubricating openings 26 to which a suitable lubricant is supplied by pipes 25.

Exhaust ports 29 are provided at the crank-ends of the engine cylinders in position to be closed at a somewhat later point in the outward travel of the engine piston 7 than that at which the ports 24 are closed by said pistons.

A pair of open-ended valveless conduits 22 and 23 are cast integral on the water jacket of each casing in communication, respectively, with the explosion cylinder through ports 24 in the explosion cylinder and with ports 12 in the pump cylinder of said casing.

The explosion-cylinder conduit of each casing is arranged to register with the pump-cylinder conduit of the other casing when said casings are secured together, thereby maintaining the explosion cylinder of each casing in free communication with the pump cylinder of the other casing. The outer ends of the conduits 22 and 23, when the casings have been secured together, are closed by removable plates, as shown especially in Fig. 1. By this construction, joints between the conduits 22 and 23 and the casings are eliminated, and said relatively long conduits will expand and contract uniformly with the casings under the variations of temperature during operation of the engine; thereby obviating the defects occurring in existing engines of this type in which the long conduits are not subjected to the same temperature variations as the engine casing.

A supply pipe 20, communicating with the conduit 22 and provided with an inwardly-opening check valve 10, constitutes an efficient connection for supplying an explosive mixture to said conduit for proper distribution to the engine.

A similar valveless conduit 23 is arranged to maintain free communication between ports 24 in the crank end of the right hand engine cylinder 2 and ports 12 in the outer end of the left hand pump cylinder 3; as shown especially in Figs. 2 and 7. A supply pipe 21, provided with an inwardly-

opening check valve 11, communicates with said conduit 23 for supplying an explosive mixture thereto, in a manner similar to that of the supply pipe 20 and conduit 22.

5 In Fig. 2 of the drawings, the pistons are shown in their extreme right hand position. During the travel of the pistons to this position, the right hand engine piston 7 has made a power stroke under the impulse of the explosive mixture ignited in its cylinder; the right hand pump piston has drawn in a charge of explosive mixture through the conduit 22 and supply pipe 20; the left hand engine piston 7 has compressed a charge of explosive mixture in its cylinder 2; and the left hand pump piston has compressed a charge of explosive mixture which was previously drawn into its cylinder through the conduit 23 and supply pipe 21. As the pistons approach 10 their extreme left hand position, the exhaust port 29 of the right hand engine cylinder 2 is uncovered by the piston 7 to permit escape of the exhausted gases of combustion and a corresponding drop of pressure in said cylinder. Upon the further travel of the pistons toward their extreme left hand position, the ports 24 in the right hand engine cylinder 2 will be uncovered, thereby permitting the charge of the explosive mixture compressed 15 in the left hand pump cylinder to enter said engine cylinder through the valveless conduit 23 and force, or sweep, the remnants of the exhaust gases through the exhaust port 29. At about the time the pistons reach 20 their extreme left hand positions, the compressed charge of explosive mixture in the left hand engine cylinder 2 is ignited and acts on the left hand engine piston 7 to drive the pistons through their right hand stroke.

25 During such travel of the pistons toward the right, the left hand pump piston will draw in a charge of explosive mixture through the conduit 23 and supply pipe 21; the right hand pump piston will compress the charge 30 of explosive mixture previously drawn into its cylinder through the conduit 22; and the right hand engine piston will compress the charge of explosive mixture previously forced into its cylinder through the valveless

conduit 23 by the left hand pump piston. Ignition will now take place in the right hand engine cylinder, and the above series of steps repeated indefinitely during the operation of the engine.

From the above description, it will be clear that my invention provides an efficient and durable multiple form of two-cycle explosive engine, in which the valveless conduits 22 and 23 constitute both suction pipes for supplying an explosive mixture to the pump cylinders and discharge pipes for conveying the compressed charges of explosive mixture from the pump cylinders to the engine cylinders; thereby insuring certainty of operation and eliminating the common defects of chattering of the valves on their seats and distortion of the valves and their seats under large ranges of temperatures incident to the operation of explosive engines.

I have illustrated and described a preferred and satisfactory construction, but obviously, changes could be made within the spirit and scope of my invention.

Having thus described my invention, what I claim as new is:

In an explosive engine, a pair of casings, each casing comprising an explosive cylinder, a pump cylinder, and a water jacket for said cylinders, a pair of open-ended valveless conduits cast integral on said water jacket of each casing and communicating, respectively, with the explosive cylinder and pump cylinder of said casing, means for securing said casings together with the explosive-cylinder conduit of each casing registering with the pump-cylinder conduit of the other casing, a closure for the outer ends of said conduits, means for supplying an explosive mixture to said conduits, pistons in said several cylinders, a crank shaft, and connections between said pistons, and crank shaft, substantially as described.

In witness whereof I have hereunto set my hand in the presence of two witnesses.

THOMAS JOSEPH EDWARD MOLDOX.
